PLATFORM AND SUPPORT YOKE FOR AN AERIAL TOWER

Thomas C. Sutphen, Columbus, Ohio, assignor to Sutphen
Fire Equipment Company, Amlin, Ohio

Filed Feb. 22, 1971, Ser. No. 117,872

Term of patent 14 years

Int. Cl. D12—13

U.S. Cl. D14—6 A

FIG. 1

FIG. 1 is a side elevational view of a platform and support yoke embodying this design attached to a telescopic boom mounted on a vehicle with the boom shown in a retracted, horizontal position.

FIG. 2 is a front elevational view of the platform and support yoke on an enlarged scale as seen with the boom in the horizontal position shown in FIG. 1.

FIG. 3 is a right side elevational view of the platform and support yoke as shown in FIG. 2.

FIG. 4 is a rear elevational view of the platform and vertical sectional view of the support yoke taken along line 4-4 of FIG. 3.

FIG. 5 is a left side elevational view of the platform and support yoke as shown in FIG. 2.

FIG. 6 is a top plan view of the platform and support yoke as shown in FIG. 2.

FIG. 7 is a bottom plan view of the platform and support yoke as shown in FIG. 2.

FIG. 8 is a perspective view on an enlarged scale of the platform and support yoke when the telescopic boom

is displaced to an angularly-elevated position with the doors to the platform in an open configuration.

The elements shown in broken lines are included for illustrative purposes only.

I claim:

The ornamental design for a platform and support yoke for an aerial tower, substantially as shown and described.
